UNITED STATES PATENT OFFICE.

THOMAS L. LOWE, OF DEVON, CONNECTICUT, ASSIGNOR TO THE LOWE MACHINERY COMPANY, OF BRIDGEPORT, CONNECTICUT, A CORPORATION OF CONNECTICUT.

LAUNDRY-DISTRIBUTING APPARATUS.

Application filed January 12, 1926. Serial No. 50,762.

The present invention relates to automatic distributing and feeding laundry apparatus, particularly for use in connection with a flat work ironer, and has for an object to provide such apparatus adapted to be employed in such relation to the ironing machine as to greatly add to its efficiency and capacity.

The method heretofore employed for feeding articles of laundry to an ironer consisted in manually placing the articles upon the moving apron of the ironer, several operators being usually employed for this purpose, and who stand in front of the machines as it is continuously operating and place the articles in flat relation upon the moving apron. This method, however, required that the operator work with great rapidity in order to get as many articles as possible in place upon the moving apron, and precluded very close or precise placement of the pieces, with the result that they were very often wrinkled or folded as they moved into the ironer, and much of the ironing space was not utilized, inasmuch as the articles could not be placed to the best advantage in the time allowed. It was therefore impossible to operate the ironer continuously and with full efficiency.

According to the present invention it is proposed to provide a distributing and feeding apparatus in which the laundry pieces may first be fed selectively by hand at a speed independent of that of the ironer, and thereafter automatically fed to the ironer in synchronism therewith in a uniform and efficient manner, and at such full speed efficiency as would be impossible with the previous method of feeding directly to the ironer by hand.

It is proposed as one adaptation of the invention to provide a series of machines arranged in cooperative relation with a common conveyor extending to the ironer, certain machines adapted to have laundry pieces fed into them by the operators and stored preparatory to automatic feeding to the ironer, while other machines previously loaded are being operated to automatically feed to the ironer. Thus the ironer may be continuously operated when desired at its full speed efficiency.

It is further proposed to provide such machines in direct line with each other, and which may be selectively operated to feed

laundry to a conveyor moving beneath all of such machines, so that the machines need not be moved into or out of relation with the ironer, but will remain stationary, and through the common conveyor will be operationally related to the ironer.

With the above and other objects in view, an embodiment of the invention is shown in the accompanying drawings, and this embodiment will be hereinafter more fully described with reference thereto, and the invention will be finally pointed out in the claims.

In the drawings:—

Fig. 1 is an elevation of one end of a laundry distributing and feeding machine, according to the present embodiment of the invention, and with the parts in position for automatic feeding to the ironer;

Fig. 2 is an elevation of the other end of the machine;

Fig. 3 is a top plan view thereof;

Fig. 4 is an elevational view showing a series of the machines in relation to the common conveyor for carrying laundry to the ironer, one of the machines being shown in position for automatically feeding to the ironer, and the other machine being shown in position for having laundry fed thereto by the operator preparatory to being fed to the ironer, and

Fig. 5 is a side view of the ironer conveyor mounting at one end of the series of machines.

Similar reference characters indicate corresponding parts throughout the several figures of the drawings.

Referring to the drawings, the machine according to the present embodiment of the invention comprises vertical side frames 10 of substantially rectangular shape and provided centrally with vertical slideways 11 in which apron roll supporting slides 12 are engaged for vertical sliding movement, and which are provided at their corners with anti-friction wheels 13 engaging the side flanges of the slideways. Within the slides 12 there are journaled the shaft ends 14 of the lower apron roll 15, the apron 16 being secured at one end to this roll and extending therefrom first over an idler roll 17, journaled at its ends in the side frame 10, at one side thereof and slightly above the common ironer conveyor, hereinafter more fully described. The apron is then carried upwardly and over

a feed roller 18 and from this roller in upwardly inclined relation over a feed roller 19, from which latter roller it extends to the upper apron roller 20, the shaft ends 21 of 5 which are journaled in rollered trucks 22 slidably supported upon upwardly inclined tracks 23 secured at their lower ends to bracket portions 24 of the frames and at their upper ends to upwardly inclined extension arms 25 formed integrally upon the rearward upper corners of the frames. The apron 16 is adapted to be wound from one roller upon the other, being wound from the lower roller to the upper roller during the 10 operation of manual feeding of laundry to the machine, and during which operation the upper roller rests upon the feed roller 19 and is rotated thereby, while the lower roller is raised with respect to the ironer conveyor. 15 20 In the operation of automatically feeding to the ironer conveyor, the apron is wound from the upper roller to the lower roller, carrying the laundry stored upon the apron about the upper roller to the ironer conveyor, the lower 25 roller being in contact with the ironer conveyor to be rotated thereby, while the upper roller is raised with respect to the feed roller 19.

As previously pointed out the series of 30 machines are arranged in line with each other above the common conveyor extending to the ironer, and at the forward side of each machine there is provided in spaced relation above such conveyor a platform 26 35 upon which the operator may stand during the operation of feeding laundry to the machine. The ironer 27 is shown at one end of the series of machines.

The ironer conveyor apron consists of a 40 series of endless tapes 28 extending at one end about a small roller 29, disposed above the upper roller 30 carrying the feeding apron 31 of the ironer, and in downwardly inclined relation from the roller 29 about a roller 45 32 journaled in the side frames of the first machine, the upper traverse of the apron 28 being held in engagement with the upper side of the roller 32 by means of an endless apron 33 extending about a roller 34 having 50 its shaft ends 35 journaled in vertical slots 36 in the side frames 10 directly above the roller 32 and over a small roller 37 journaled above the roller 29. This apron 33 is adapted to move with the conveyor 28 between the rollers 32 and 29 to retain the laundry pieces in flat relation upon the conveyor until they pass over the roller 29 and into the ironer. The conveyor extends from the roller 32 in horizontal relation beneath 60 the several machines to a roller 38 disposed beyond the last machine of the series and mounted for horizontal compensating adjustment movement in a bracket 39.

In passing through the several machines 65 the conveyor engages above and below

spaced horizontal rollers 40 and 41 journaled in the lower portions of the frame 10 of each of the machines, and which rollers are positively driven, as will presently more fully appear, for the purpose of driving the 70 conveyor.

In the last machine of the series there is provided a tension roller 42 over which the lower traverse of the conveyor passes and which roller insures a positive engagement 75 of the conveyor with the feed rollers 40 and 41. As before pointed out, the lower apron roller 15 of the machine is adapted to be lowered into engagement with the conveyor during the automatic feeding to the ironer, 80 the same being shown in this position in the left hand machine, Fig. 4, and in which position the said roller rests upon the rollers 40 and 41 depressing the conveyor between these rollers. The conveyor passes in flat-wise relation over the rollers in the raised position of the lower apron roller, as indicated in the right hand machine, during the manual operation of feeding clothes into the machine. 90

For the purpose of taking up slack in the conveyor when the same is moved into flat position after having been depressed by the lower apron roller, and thereby maintaining a positive engagement with the feed rollers 95 40 and 41, the roller 38 is adapted to yield in a horizontal direction, an outward pull being maintained thereon to take up any slack in the conveyor by means of a drum 43 supported in a suitable bracket 44 and to 100 which one end of a cable 45 is secured, said cable passing beneath a roller 46 and over a roller 47 and being provided at its other end with a weight 48 which tends to turn the drum in counter-clockwise direction. The 105 shaft 49 of the drum is provided with a gear 50 meshing with a rack 51 mounted for horizontal sliding movement and to the end of which the adjustable roller 38 is rotatably secured; thus rotation of the drum 43 110 through the action of the weight 48 will impart an outward movement to the roller 38, while an inward pull by the conveyor upon the roller 38 will lift the weight.

The rollers 40 and 41 are adapted to be 115 driven directly from the ironer in synchronism therewith and for this purpose a gear 52, driven by the ironer, is connected by a sprocket chain 53 with a gear 54 mounted in a suitable bearing bracket 55 and having 120 a spiral gear 56 secured upon its shaft which meshes with a spiral gear 57 secured upon one end of a shaft 58 extending horizontally in relation to the several machines, said shaft 58 being provided within each of the 125 machines with spiral gears 59 and 59^a which mesh with spiral gears 60 and 61 carried upon the shafts of the roller 40 and 41.

In order to maintain the laundry upon the apron during the automatic feeding of 130

the work to the ironer conveyor as said apron traverses between the guide rollers 18 and 17, an endless apron 62 is extended between an upper roller 63 and a lower roller 64, said upper roller having its shaft ends 65 slidably engaged in inclined slots 66 in the side frames so that said roller frictionally bears against the roller 18 and is driven thereby. The aprons between said rollers 18 and 17 are tensioned by means of a roller 67 engaged at the inner side of the apron 62 and having its shaft ends 68 slidably supported in horizontal slots 69 in the side frames, and in which slots said shaft is adapted to be adjusted to regulate the tension on said aprons.

At the forward side of the machine, and disposed above the traverse of the apron 16 extending between the rollers 18 and 19, there is provided an adjustable loading and feeding apron 70 extended at its outer end about a relatively large diameter roller 71 having its shaft ends 72 journaled in the side frames 10 and extended at its inner end about a relatively small roller 73 disposed directly above the roller 19, said rollers 72 and 73 being connected together by tapered side plates 74, pivotally mounted at their outer ends upon the shaft 72, and rotatably supporting the roller 73 at their inner ends. The apron 70 is preferably in the form of a plurality of parallel tapes and adjacent and above the roller 73 is engaged by a gravity friction roller 75, having its shaft ends 76 engaged for vertical movement in vertically slotted ears 77 formed upon the side plate 74 and serving to retain the laundry pieces in flatwise relation upon the apron 70 as the same are engaged and fed by the apron 16 into relation about the upper roller 20. The apron 70 is tensioned by means of a roller 78 supported at its ends by lever arms 79 pivotally mounted at 80 upon the side plate 74, said roller having its shaft ends 81 engaged in slotted portions 82 of the side plates whereby the weight of the roller bears downwardly upon the lower traverse of the apron. The driving mechanism for the apron 16 and the apron 70, and which will be presently more fully described, is such that the apron 70 is operated at a slightly slower speed than the apron 16, providing a retarding tension upon the laundry pieces as they are fed from the apron 70 to the apron 16, which in cooperation with the friction weight roller 75 provides a retarding tension upon the laundry pieces, causing them to stretch slightly as they are fed upon the apron 16 and which insures their disposition in the apron being rolled about the upper roller in a smooth flat relation.

The several machines are adapted to be driven from a single source and for this purpose an electric motor 83 is provided, which through a flexible coupling 84 drives

a horizontal shaft 85 extending to the several machines at one side, and provided in relation to each of said machines with a worm drive 86 disposed within a supporting housing 87, and meshing with a worm gear 88, provided upon its shaft 89 with a sprocket gear 90 connected by a sprocket chain 91 to a sprocket gear 92 mounted upon the shaft 72, and adapted to be connected by means of a sliding clutch 93 to a sprocket gear 94 also mounted upon said shaft 72. The clutch 93 is adapted to be shifted by means of a bell-crank lever 95, having a forked upper end 96 engaging the clutch and connected at its lower end by a link 97 to a foot lever 98 pivotally mounted upon the side frame at 99, this lever being in such relation with respect to the platform 26, that the operator standing thereon may engage and disengage the clutch at will, so that as the foot lever is depressed the machine will operate, and will stop when the lever is raised, it being understood that the machine will be operated in this intermittent manner to permit the operators to selectively arrange the laundry pieces upon the apron 70, and thereupon cause them to be fed to the apron 16.

The sprocket gear 94 is connected by a sprocket chain 100 to a sprocket gear 101 mounted upon the shaft 102 of the apron roller 19, and adapted to be connected to said shaft by means of a clutch 103 disposed upon the shaft 102 at one side of the machine, and adapted to be operated from the other side of the machine by means of an elongated pull-rod 104 extending through guide brackets 105 and 106 supported upon the side frames, and connected at its end to a hand lever 107 pivotally supported at 108 upon the bracket 106. The projecting end of the shaft 102 is journaled in the bearing bracket 109, and at the inner side of said bracket there is secured upon said shaft a sprocket gear 110 connected by a sprocket chain 111 to a sprocket gear 112 secured upon the shaft 113 of the roller 18, and through which said roller 18 is adapted to be driven in synchronism with the roller 19.

As the roller 71 is of slightly smaller diameter than the roller 19 the speed of travel of the feeding apron 70 is slightly less than that of the apron 16, the sprocket wheels 94 and 101 being of equal diameter. During the normal loading operation of the machine, the clutch 103 is connected and the whole machine intermittently controlled by operation of the clutch 93 through the foot lever 98. During the feeding operation to the ironer both clutches 93 and 103 are disconnected, the clutch 103 disconnecting the rolls 18 and 19 from the gearing, so that they are free to rotate.

During the loading operation the apron 70 and its supporting frame are adapted to

be moved into substantial engaging relation with the roller 19, as shown in full lines in the right hand machine, Fig. 4, while in the feeding operation to the ironer it is adapted 5 to be raised with respect to said roller as shown in full lines in Fig. 1 and in the left hand machine, Fig. 4. For the purpose of effecting this raising and lowering movement, a hand lever 114 is secured at one 10 end to a rock-shaft 115 extending transversely across the machine and rotatably supported at its ends in standards 105 mounted upon the upper side of the side frames 10, and adjacent each of said standards, lever arms 117 are provided upon the shaft 115, these arms rotatably supporting between their inwardly projecting ends a transverse bar 118, and being pivotally connected at their outwardly projecting ends 15 20 25 29 30 35 40 45 50 55 60 65 70 75 80 85 90 95 100 105 110 115 120 125 130 winding shaft 132 supported at its ends in suitable brackets 133, and provided at one end with a hand wheel 134 by means of which said shaft may be first turned to take up the slack in the cable caused during the loading operation as the apron rolled about the upper roller 20 has been increased in diameter, and further turned to raise said roller into spaced relation to the roller 19 through further winding of the cable on 70 said shaft. The shaft 132 is thereupon adapted to be secured in such position by means of a clutch 135 which upon being shifted connects it to a worm gear 136, meshing with a worm 137 mounted in a suitable bearing housing 138, and adapted to be driven through a coupling 139 by an electric motor 140 supported upon a bracket 141 secured to the side frame 10 at one side. This motor is normally inoperative and the meshing relation of the worm 137 with the gear 136 is such as to lock the latter, so that when the clutch 135 is engaged the cable winding shaft 132 is held against rotation. The 80 clutch 135 is adapted to be shifted by means of a forked lever 142 connected by a pull rod 143 to a hand lever 144 disposed in accessible relation adjacent the hand wheel 134. 85 90 95

As the machine is operated to feed the laundry pieces to the ironer conveyor the upper roll and apron gradually decreases in diameter and the lower roll and apron increases in diameter and in order to maintain a substantially constant spaced relation between the surface of the apron upon the upper roller and the roller 19 and to maintain substantially the same relation to the doffer bar 126 so that the laundry pieces may be disturbed as little as possible should they stick to the upper roll and have to be removed therefrom by the doffer bar, the upper roller is adapted as it decreases in diameter to a predetermined extent to be lowered sufficiently to compensate for this decrease through operation of the motor 140, which through the worm 137 and gear 136 reels off the cable 130 and lowers the roller 20 to such desired position. For the purpose of automatically controlling this action, a rod 145 is secured in depending relation upon the rod 118 and is disposed at its lower end between spaced stop fingers 146 and 147, provided upon a pull rod 148, pivotally secured at one end to a switch lever 149, connected to a toggle switch 150 secured upon the arm 117 at one side, this switch being connected by suitable lead wires 151 to the lead end control switch 152 of the motor 140, said switch 152 being mounted upon the bracket 141.

Referring particularly to Fig. 1, the operation of the switch mechanism is as follows:—

As the diameter of the rolled apron upon 130

the upper roller decreases in size, the doffer bar 127 follows its surface, through the action of the spring 128, gradually rotating the bar 118 in clockwise direction, moving the 5 rod 145 gradually into engagement with the stop 146 upon the rod 148, and as this movement continues shifts the rod 148 to the right to a point where the switch lever 149 is thrown into circuit closing relation with 10 a snap action, causing the motor 140 to be started up, whereupon the trucks 22 are lowered upon the tracks 23 through gravity. During this lowering movement, the doffer bar 127 is swung downwardly, rotating the 15 bar 118 in counter-clockwise direction and causing the rod 145 to engage the stop 147 of the rod 148, and at a predetermined point to throw the switch in the opposite direction to open the circuit and thereby stop the 20 operation of the motor. This operation is repeated at intervals throughout the feeding of the laundry to the ironer and maintains a substantially constant spaced relation at the point of emergence of the laundry pieces 25 from the upper roller.

During the loading operation the upper roller is lowered into engagement with the roller 19 through disconnecting the clutch 135 and reeling off the cable 130 through 30 operation of the hand wheel 134, while the lower roller 15 is raised in spaced relation with respect to the ironer conveyor. For this purpose the supporting slides 12 are respectively connected at their upper ends 35 to cables 155 wound about and connected at their upper ends to a winding shaft 156 journaled at its ends in the upper portions of the side frames 10, and provided at one end with a hand wheel 157 adapted through 40 rotation to wind the cable upon said shaft to lift the lower roll to the dotted line position as shown in Fig. 2, the same being held in such position by suitable pawl and ratchet mechanism 158.

45 I have illustrated and described a preferred and satisfactory embodiment of my invention, but it is obvious that changes may be made therein within the spirit and scope thereof, as defined in the appended 50 claims.

Having thus described my invention what I claim and desire to secure by Letters Patent is:—

1. In a machine of the character described, 55 an apron, a pair of spaced rolls respectively connected to the ends of said apron whereby the apron is adapted to be wound from one upon the other, drive means with which said rolls may have frictional driving engagement, and means for moving said respective rolls into spaced relation with said drive means whereby as one roll is rotated by its drive means, the other roll may be free of its drive means.

60 2. In a machine of the character described,

an apron, a pair of spaced rolls respectively connected to the ends of said apron whereby the apron is adapted to be wound from one upon the other, and to have laundry pieces placed thereon to be wound with said apron 70 about one of said rolls when said apron is moved in one direction, and a conveyor positioned to receive said pieces during movement of said apron in the other direction. 75

3. In a machine of the character described, 80 an apron, a pair of spaced rolls respectively fixed to the ends of said apron, a driving roller over which said apron passes in moving from one of said rolls to the other, and means for supporting one of said rolls in position to have frictional engagement by its weight with said driving roller to be rotated thereby.

4. In a machine of the character described, 85 an apron, a pair of spaced rolls respectively fixed to the ends of said apron, a driving roller journaled in fixed position and over which said apron passes in moving from one of said rolls to the other, and means for supporting one of said rolls at one side and 90 above said driving roller in position to have frictional engagement with said driving roller to be rotated thereby.

5. In a machine of the character described, 95 an apron, a pair of spaced rolls respectively fixed to the ends of said apron, a drive roller over which said apron passes in moving from one of said rolls to the other, means for supporting one of said rolls at one side and above said driving roller in position to 100 have frictional engagement with said driving roller to be rotated thereby, said means comprising a diagonally disposed support for said roll inclined downwardly toward said drive roller whereby the weight of said 105 roll and apron wound thereon engages it with said drive roller.

6. In a machine of the character described, 110 an apron, a pair of spaced rolls respectively connected to the ends of said apron, a drive roller over which said apron passes in moving from one of said rolls to the other, means for supporting one of said rolls at one side and above said driving roll in position to 115 have frictional engagement with said driving roller to be rotated thereby, said means comprising a diagonally disposed support for said one roll inclined downwardly toward said drive roller whereby the weight of said one roll and apron wound thereon 120 engages it with said drive roller, means for lifting said one roll upwardly upon said inclined support into spaced relation with said driving roller, and drive means for the other of said rolls for rotating the same in opposite direction to the direction of rotation of said one roll.

7. In a machine of the character described, 125 an apron, a pair of spaced rolls respectively connected to the ends of said apron, said 130

apron adapted to be wound from one of said rolls upon the other, a guide support for one of said rolls, a guide support for the other of said rolls, drive means disposed adjacent to 5 said first support, a horizontal conveyor disposed adjacent to said second support, and means for moving said respective rolls into and out of driven relation with said drive means and said conveyor, whereby said 10 apron is wound upon said first mentioned roll during engagement of said roll with said drive means, and is wound on said last mentioned roll during engagement of said last mentioned roll with said conveyor, whereby said 15 laundry may be wound with said apron upon said first roll or fed by said apron onto said conveyor.

8. In a machine of the character described, an apron, a pair of spaced rolls 20 respectively connected to the ends of said apron, said apron adapted to be wound from one of said rolls upon the other, an inclined support for one of said rolls, a vertical support for the other of said rolls, drive means 25 disposed adjacent to said inclined support, a horizontal conveyor disposed adjacent to said vertical support, means for moving said respective rolls into and out of driven relation with said drive means and said 30 conveyor whereby said apron is wound upon said first mentioned roll during driving of said roll by said drive means, and is wound on said last mentioned roll during driving of said roll by said conveyor, whereby 35 laundry may be wound with said apron upon said first roll or fed by said apron upon said conveyor.

9. In a machine of the character described, an apron, a pair of spaced rolls 40 respectively connected to the ends of said apron, means for rotating said rolls whereby the apron is wound from one upon the other, a secondary loading apron for delivery to said first apron, means for driving said secondary apron, and means for stopping and starting the movements of said aprons at 45 will.

10. In a machine of the character described, an apron, a pair of spaced rolls 50 respectively connected to the ends of said apron, means for rotating said rolls whereby the apron is wound from one upon the other, a secondary loading apron for delivery to said first apron, means for driving said secondary apron, and means for stopping and starting the movements of said aprons at will independently of each other. 55

11. In a machine of the character described, an apron, a pair of spaced rolls 60 respectively connected to the ends of said apron, means for rotating said rolls whereby the apron is wound from one upon the other, a secondary loading apron for delivery to said first apron, means for driving said secondary apron, means for stopping 65

and starting the movement of said aprons at will, and means for moving said secondary apron into and out of cooperative relation with said first apron.

12. In a machine of the character de- 70 scribed, an apron, a pair of spaced rolls respectively connected to the ends of said apron, means for rotating said rolls whereby the apron is wound from one upon the other, a secondary leading apron for feeding 75 to said first apron, means for driving said secondary apron at a slower speed than the speed of movement of said first apron, and means for stopping and starting said aprons at will. 80

13. In a machine of the character de- 85 scribed, an apron, a pair of spaced rolls respectively connected to the ends of said apron, means for rotating said rolls whereby the apron is wound from one upon the other, a secondary loading apron for feeding laundry pieces to said first apron, means for driving said secondary apron at a slower speed than the speed of movement of said first apron, means for stopping and starting 90 the movements of said aprons at will, and friction means engaging the surface of said secondary apron at its delivery end adapted to exert a pull on said laundry pieces as they are delivered to said first apron. 95

14. In a machine of the character de- 100 scribed, an apron, a pair of spaced rolls respectively connected to the ends of said apron, means for rotating said rolls whereby the apron is wound from one upon the other, a secondary loading apron for feeding laundry pieces to said first apron, means for driving said secondary apron at a slower speed than the speed of movement of said first apron, means for stopping and starting 105 the movements of said aprons at will, and a gravity friction roller engaging the surface of said secondary apron at its delivery end adapted to exert a pull on said laundry pieces as they are delivered to said 110 first apron.

15. In a machine of the character de- 115 scribed, an apron, a pair of spaced rolls respectively connected to the ends of said apron, a feed roller over which said apron passes in moving from one roll to the other, means for moving one of said rolls and apron wound thereon into and out of frictional engagement with said feed roller, a secondary loading apron for feeding laundry pieces to said first apron, said roll and apron being engaged with said feed roller during delivery of laundry pieces from said secondary apron to grip the pieces between its convolutions and draw them from said 120 secondary apron.

16. In a machine of the character de- 125 scribed, an apron, a pair of spaced rolls respectively connected to the ends of said apron, a feed roller over which said apron 130

- passes in moving from one roll to the other, means for moving one of said rolls and apron thereon into and out of frictional engagement with said feed roller, a secondary loading apron for feeding laundry pieces to said first apron, said one roll and apron being engaged with said feed roller during delivery of laundry pieces from said secondary apron to cause the convolutions of said apron to grip the pieces and draw them from said secondary apron, and means for exerting a retarding action on said laundry pieces as they are drawn from said secondary apron whereby they are smoothed and flattened.
17. In a machine of the character described, an apron, a pair of spaced rolls respectively connected to the ends of said apron, a feed roller over which said apron passes in moving from one roll to the other, means for moving one of said rolls and apron thereon into and out of frictional engagement with said feed roller, a secondary loading apron for feeding laundry pieces to said first apron, said roll and apron being disengaged with said feed roller during delivery of laundry pieces from said secondary apron to cause the convolutions of said apron to grip the pieces and draw them from said secondary apron, and means for moving said secondary apron at a slower speed than said first apron whereby a retarding action is exerted on said laundry pieces as they are drawn from said secondary apron.
18. In a machine of the character described, an apron, a pair of spaced rolls respectively connected to the ends of said apron, a feed roller over which said apron passes in moving from one roll to the other, means for moving one of said rolls with the apron thereon into and out of frictional engagement with said feed roller, and means adapted while said roll and apron thereon is out of contact with said feed roller to move said roll towards said feed roller as the apron is wound therefrom whereby a substantially constant spaced relation is maintained between the surface of said apron, as its diameter on the roll decreases, and the surface of said feed roller.
19. In a machine of the character described, an apron, a pair of spaced rolls respectively connected to the ends of said apron, a feed roller over which said apron passes in moving from one roll to the other, means for moving one of said rolls and apron wound thereon into and out of frictional engagement with said feed roller, means adapted to impart movement to said roll towards said feed roller, an electric motor for driving said means, and switch mechanism cooperating with said apron on said roll whereby as said winding decreases in diameter, through winding off of said apron to a predetermined extent, said motor is operated to impart movement to said roll towards said feed roller, and upon a predetermined movement of said roll towards said feed roller said motor is stopped.
20. In a machine of the character described, an apron, a pair of spaced rolls respectively connected to the ends of said apron, a feed roller over which said apron passes in moving from one roll to the other, means for moving one of said rolls and apron wound thereon into and out of frictional engagement with said feed roller, means adapted to impart movement to said roll towards said feed roller, an electric motor for driving said means, and switch mechanism cooperating with the surface of said apron as wound on said roll whereby as said winding decreases in diameter, through winding off of said apron to a predetermined extent, said motor is operated to impart movement to said roll towards said feed roller, and upon a predetermined movement of said roll towards said feed roller said motor is stopped.
21. In a machine of the character described, an apron, a pair of spaced rolls respectively connected to the ends of said apron, a feed roller over which said apron passes in moving from one roll to the other, means for moving one of said rolls and apron wound thereon into and out of frictional engagement with said feed roller, means for imparting movement to said roll towards said feed roller, an electric motor for driving said means, switch mechanism for starting and stopping said motor, and a scraper bar yieldably engaging the surface of said wound apron to remove laundry pieces therefrom and cooperatively connected to said switch mechanism, whereby as said roll decreases in diameter, through winding off of said apron to a predetermined extent, said motor is operated to impart movement to said roll towards said feed roller, and upon a predetermined movement of said roll towards said feed roller said motor is stopped.
22. In a machine of the character described, an apron, a pair of spaced rolls respectively connected to the ends of said apron, a feed roller over which said apron passes in moving from one roll to the other, means for moving one of said rolls and apron wound thereon into and out of frictional engagement with said feed roller, means to impart movement to said roll towards said feed roller, an electric motor for driving said means, a secondary loading apron movable between feeding and non-feeding relation to said first apron, and switch mechanism for starting and stopping said motor controlled by the apron wound on said roll in the non-feeding position of said loading apron and during the spaced relation of said roll and apron wound thereon.

- and said feed roller, whereby as said apron winding decreases in diameter through winding off of said apron to a predetermined extent, said motor is operated to impart movement to said roll towards said feeding roller, and upon a predetermined movement of said roll towards said feeding roller said motor is stopped.
23. In combination, an ironer, a conveyor for feeding laundry pieces to said ironer in synchronism therewith, a plurality of loading and feeding devices, and means for selectively operating each of said devices to receive and store laundry pieces arranged for ironing or to feed such stored and arranged pieces to said conveyor whereby one of said devices may be feeding to said conveyor while another of said devices is receiving and storing laundry pieces.
24. In combination, an ironer, a conveyor for feeding laundry pieces to said ironer in synchronism therewith, a laundry loading and feeding machine including a pair of spaced rolls, an apron connected at its respective ends to said rolls and adapted to be wound from one upon the other, drive means for one of said rolls adapted to be operatively connected therewith and disconnected therefrom for driving said apron in synchronism with said conveyor to feed laundry pieces from said apron to said conveyor, and means for rotating said other roll, when said one roll is disconnected from its drive means, in opposite direction to the direction of rotation imparted by said drive means.
25. In combination, an ironer, a conveyor for feeding laundry pieces to said ironer, means for driving said conveyor in synchronism with said ironer, a laundry loading and feeding machine for feeding to said conveyor and including a pair of spaced rolls, an apron connected at its respective ends to said rolls to be wound from one upon the other, one of said rolls being disposed adjacent to said conveyor and movable into and out of operative connection with said drive means, said roll when in operating connection with said drive means being rotated thereby and feeding laundry pieces on said apron to said conveyor, and means for rotating said other roll when said first roll is out of operating connection with said drive means in the opposite direction to the direction of rotation imparted by said drive means.
26. In combination, an ironer, a conveyor for feeding laundry pieces to said ironer in synchronism therewith, a laundry loading and feeding machine disposed adjacent to said conveyor and including a pair of spaced rolls, an apron connected at its respective ends to said rolls and adapted to be wound from one upon the other, one of said rolls being disposed adjacent to said conveyor and movable into an out of engagement therewith, said roll during engagement with said conveyor being rotated thereby and acting to feed laundry pieces from said apron to said conveyor, and means for rotating said other roll when said first roll is out of engagement with said conveyor in the opposite direction to the direction of rotation imparted by said conveyor.
27. In combination, an ironer, an endless conveyor for feeding laundry pieces to said ironer, a pair of drive rollers frictionally engaged beneath the upper traverse of said conveyor for driving it in synchronism with said ironer, a laundry loading and feeding machine disposed adjacent to said conveyor and including a pair of spaced rolls, an apron connected at its respective ends to said rolls and adapted to be wound from one upon the other, one of said rolls being disposed adjacent to said conveyor and movable into and out of engagement therewith between said spaced drive rollers, said roll during such engagement with said conveyor being rotated thereby in synchronism with the ironer to feed laundry pieces from said apron to said conveyor, and means for rotating said other roll when said first roll is out of engagement with said conveyor in the opposite direction to the direction of rotation imparted by said conveyor.
28. In combination, an ironer, an endless conveyor for feeding laundry pieces to said ironer, a pair of drive rollers frictionally engaged beneath the upper traverse of said conveyor to drive it in synchronism with said ironer, a laundry loading and feeding machine disposed adjacent to said conveyor and including a pair of spaced rolls, an apron connected at its respective ends to said rolls and adapted to be wound from one upon the other, one of said rolls being disposed adjacent to said conveyor and movable into and out of engagement therewith between said spaced drive rollers, said roll during engagement with said conveyor being rotated by said drive rollers in synchronism with the ironer to feed laundry pieces from said apron to said conveyor, and means for rotating said other roll when said first roll is out of engagement with said conveyor in the opposite direction to the direction of rotation imparted by said conveyor, and means exerting a yielding pull on said conveyor to permit it to yield upon engagement of said first roll thereon.
29. In combination, an ironer, a conveyor for feeding laundry pieces to said ironer, a plurality of loading and feeding machines disposed in feeding relation to said conveyor and each including a pair of spaced rolls, an apron connected at its respective ends to said rolls, said respective rolls being rotatable in opposite directions to wind said apron from one upon the other whereby clothes loaded thereon may be wound with

said apron about one of said rolls during movement in one direction, and during movement in the other direction may be fed to said conveyor.

- 5 30. In combination, an ironer, a conveyor for feeding laundry pieces to said ironer, a plurality of loading and feeding machines disposed in feeding relation to said conveyor and each including a pair of spaced 45 rolls, an apron connected at its respective ends to said rolls, said respective rolls being rotatable in opposite directions to wind said apron from one upon the other whereby clothes loaded thereon may be wound about 50 10 rolls, an apron connected at its respective ends to said rolls, said respective rolls being rotatable in opposite directions to wind said apron from one upon the other whereby 55 clothes may be loaded thereon and wound therewith about one of said rolls during movement in one direction and may be fed to said conveyor during movement in the opposite direction, and means for rotating 60 said rolls selectively in one or the other 65 direction.
- 15 31. In combination, an ironer, a conveyor for feeding laundry pieces to said ironer, 70 a plurality of loading and feeding machines disposed above said conveyor in spaced relation to each other, a conveyor drive means having engagement with said conveyor adjacent to each machine and driving said 75 20 conveyor in synchronism with the ironer, each of said machines including a pair of spaced rolls, an apron connected at its respective ends to said rolls and adapted to be wound from one upon the other, one of 80 30 said rolls being disposed adjacent to said conveyor and movable into and out of engagement with said conveyor at one of said conveyor drive means, said roll during engagement with said conveyor being rotated 85 35 by movement thereby in synchronism with the ironer, and means for rotating said other 40 40

roll when said first roll is out of engagement with said conveyor in opposite direction to the direction of rotation imparted by said conveyor.

45 32. In combination, an ironer, a conveyor for feeding laundry pieces to said ironer, a plurality of loading and feeding machines disposed in feeding relation to said conveyor and each including a pair of spaced 50 rolls, an apron connected at its respective ends to said rolls, said respective rolls being rotatable in opposite directions to wind said apron from one upon the other whereby 55 clothes may be loaded thereon and wound therewith about one of said rolls during movement in one direction and may be fed to said conveyor during movement in the opposite direction, and means for rotating 60 said rolls selectively in one or the other 65 direction.

70 33. In combination, an ironer, a conveyor for feeding laundry pieces to said ironer, a plurality of loading and feeding machines disposed in feeding relation to 65 said conveyor and each including a pair of spaced rolls, an apron connected at its respective ends to said rolls, said respective rolls being rotatable in opposite directions 70 to wind said apron from one upon the other whereby clothes loaded thereon may be wound therewith about one of said rolls when moving in one direction and may be fed to said conveyor when moving in the opposite direction, means for rotating said 75 rolls selectively in either direction and means for operatively disconnecting said rotating means from said rolls.

Signed at Bridgeport, in the county of Fairfield and State of Connecticut, this 5th 80 day of January, A. D. 1926.

THOMAS L. LOWE.
